UNITED STATES PATENT OFFICE.

CHARLES R. BRYSON, OF PITTSBURGH, PENNSYLVANIA.

DRILL-JAR.

1,200,465.

Specification of Letters Patent. Patented Oct. 10, 1916.

Application filed March 24, 1915. Serial No. 16,617.

To all whom it may concern:

Be it known that I, CHARLES R. BRYSON, a citizen of the United States, residing at Pittsburgh, in the county of Allegheny and State of Pennsylvania, have invented a new and useful Improvement in Drill-Jars, of which improvement the following is a specification.

My invention relates to jars for drills employed in sinking or boring deep wells.

The objects are, to produce a jar of maximum efficiency and strength, simple in construction, and to produce a jar the working surfaces of which are of uniform strength and at the same time avoid in the construction thereof the welding of any of the parts together. I accomplish these objects by means of the device hereinafter more particularly described, reference being had to the accompanying drawings, forming part hereof, in which—

Figure 1 is a side elevation of the piston member. Fig. 2 is an end view of the same looking from the right. Fig. 3 is a transverse section on the line 1—1 of Fig. 4. Fig. 4 is a side elevation of the cylinder member of the jar before the same is connected to the piston member. Fig. 5 is a side elevation partly in section of the jar assembled.

In constructing my improved jar, I take a blank similar in form to the member 1, shown in Fig. 4. I core, ream, or otherwise form longitudinally therein, the bore, 2, the side walls of which are provided with openings, 3, 3, at points equidistant from each other, as shown in Fig. 3. The open end of the bore 2 is initially flared or enlarged, with the longitudinal slots 3 extending to the base of the said flared end, as indicated by Fig. 4. I then, after heating the same, insert therein the shank member, 4, of the piston, 5, the lower end of said shank being provided with outwardly projecting wings, 6, adapted to enter the openings, 3, in the walls of the cylinder, 1, and with a rounded end or hammer portion, 7. The base of the bore 2 is provided with a depression corresponding in shape to the rounded end or hammer portion 7 of the piston 5 so as to minimize the usual flattening of the metal caused by the continual pounding of the hammer against the seat of the cylinder member. I then shrink, swage, or otherwise reduce the enlarged end of the said cylinder member around the shank, 4, adjacent to the

shoulder, 8, on the piston member, as shown in Fig. 5.

The jars thus produced are provided with a socket, 9, formed in the solid end, and a threaded extension, 10, at the other end for the purpose of connecting the same with a string of tools.

The advantages of my improved jars are that a very strong tool of this description is produced without welding and the working parts are of uniform and corresponding strength.

The disposition of the wings upon the shank member of the piston and the recesses in which the same are seated formed in the walls of the cylinder member are so disposed that the working surfaces of both parts are equidistant and a maximum degree of strength secured.

Having described my invention, what I claim and desire to secure by Letters Patent, is:

1. A drill jar comprising a socket, and a stem snugly and slidably engaging in the socket and having at least three equally spaced apart sides in contact with the inner wall of the socket, the stem also having at least three anvil members each radiating from between two adjacent sides, the socket having spaced apart longitudinally extending slots in its walls, one for each anvil member, to receive the same and connect the socket and stem together and hold the same from relative lateral vibration.

2. A drill jar for comprising a link provided with a cylindrical stem having more than two anvil members radiating from the sides at the outer end thereof, and a second link having a cylindrical socket in its inner terminal for the reception of said stem with a sliding fit, the second link also having more than two elongated slots in its sides terminating short of the inner end thereof for the reception of the anvil members to interlock and guide the links, and having abutting faces for the sides of the cylindrical stem at more than two sides to prevent vibration of the links, said first link having an annular striking shoulder adapted to receive the closed inner end of said second link thereagainst.

3. A drill jar comprising a pair of links, one link having a stem with three anvil members equi-distantly spaced thereabout and having engaging faces between said anvil members, the second link having a

socket to closely receive, house, and guide the stem, the second link also having three equi-distantly spaced apart elongated slots in the sides thereof to receive the three anvil 5 members and provide bearing faces between the slots to support the engaging faces on the stem and hold the links from lateral vibration in any direction and in true longitudinal alinement at all times.

10 4. A drill jar comprising links or sections each made from a single piece of metal, one of the links or sections being hollowed out from one end inwardly forming a cylindrical socket and provided with elongated slots 15 in the wall thereof, which slots begin at the inner end of the socket and extend part way along the wall thereof and are in communication with the socket, a cylindrical stem formed on the inner terminal of the other 20 section or link, and a series of integral anvil

members formed at the outer terminal of the stem and corresponding in number to the slots, said stem being received in the socket with a close sliding fit and completely surrounded by the same throughout the length 25 of the stem in the socket except where exposed through the slots, and the anvil members entering the slots for forming a permanent interlocking connection between the two sections or links, said anvil members being of less length than the said slots for forming a sliding engagement between the two members. 30

In testimony whereof, I have hereunto signed my name in the presence of two sub- 35 scribing witnesses.

CHARLES R. BRYSON.

In the presence of—

ELIZABETH TROLLOPE,
CLARENCE A. WILLIAMS.
